INVENTOR:

W. M. Hazel,

UNITED STATES PATENT OFFICE.

WILLIAM M. HAZEL, OF NEW YORK, N. Y.

BUTTON-FASTENER.

SPECIFICATION forming part of Letters Patent No. 380,112, dated March 27, 1883.

Application filed April 11, 1883. Serial No. 91,328. (No model.)

To all whom it may concern:

Be it known that I, WILLIAM M. HAZEL, a citizen of the United States, and a resident of New York, in the county of New York 5 and State of New York, have invented certain new and useful Improvements in Button-Fastenings, of which the following is a specification.

My invention relates to certain improvements in staple-fastenings for attaching buttons to shoes and other apparel without an under plate, and particularly to the fastening for which Letters Patent of the United States, No. 272,836, bearing date of February 20, 15 1883, were granted me, on which patent my present device is an improvement; and it consists, first, in beveling the ends of the concaved prongs on their edges; second, in flattening and broadening the prongs and then 20 pressing them into a concavo-convex form, and, third, in forming the body of the loop round, flattening and broadening the prongs on their outer surface, and convex on their under surface, all of which will be more fully 25 described hereinafter.

In the accompanying drawings, which are enlarged, Figure 1 represents my invention with a loop and two depending concaved prongs which are beveled on their edges near 30 their ends to a point; Figs. 2, 3, 4, and 7, modifications of Fig. 1. Fig. 5 represents a sectional view of Fig. 1 and shows the concaved form of prongs. Fig. 6 represents the fastening and a button attached to fabric, and 35 Fig. 8 a novel form of die for clinching same.

Similar letters of reference indicate like parts in the several drawings.

My improved device in its preferred form is made from sheet metal bent in the form of a 40 staple with its ends beveled to a point on their edges at *c c*, and its prongs *A A* pressed concavo-convex from the curve of the loop *B* to their extreme ends, so that when the fastening is forced through the fabric and strikes 45 the novel die shown in Fig. 8 of the drawings its prongs are deflected in opposite directions up against the under side of said fabric, when that portion *a a* of prongs at the immediate end of the curve of the loop *B* flattens and

broadens, as does also that portion *a' a'* below 50 the beveled ends where they turn up into the fabric, while the intermediate portions of prongs *A A*—that is, between the broadened and flattened parts referred to—retain their concaved form, which condition gives great 55 strength and general efficiency to the fastening, while the material between the prongs below the loop *B* and eye of button holds the fastening firmly in the position in which it is 60 set.

In Figs. 2, 3, 4, and 7 of the drawings I show modified forms of Fig. 1, either of which may be employed without departing from the spirit of my invention. In Fig. 2 I make the beveled edges flat on their ends and the same 65 thickness as the prongs. In Fig. 3 I make the bevel longer. In Fig. 4 I flatten the end and bevel it as in Fig. 2, and in Fig. 7 I make the fastening of round wire and flatten the prongs, bevel their ends, and then press the 70 said prongs into a concavo-convex form, or, if preferred, they may be simply flattened and broadened on their upper and convexed on their under surface. In either event the same 75 desirable result will be produced—that is, increased strength and endurance to the prongs and a broad and rounded portion of prong next to the person of the wearer—the said broadened and rounded condition enabling 80 them to better maintain their position when subjected to the strain from button when in use.

In my patent already named, on which my present device is an improvement, I notched the ends of my prongs, so that the said prongs 85 might terminate in additional small penetrating prongs; but I have found that in certain cases it is more desirable that the said main prongs should terminate in central points, and have consequently beveled them in my present device, as shown and described, to accomplish this result, and consider that I have therein made a valuable improvement over my device as heretofore patented to me.

Having fully described my improved device and the manner of applying the same, what I claim, and wish to secure by Letters Patent, is—

An improved button fastener, consisting of the loop B and the prongs A. A, of greater width than the said loop, each of equal width throughout and concavo-convex in cross-section, the 5 ends of said prongs being each beveled on their edges to a single point, substantially as set forth.

Signed at New York, in the county of New York and State of New York, this 10th day of April, A. D. 1883.

WM. M. HAZEL.
